UNITED STATES PATENT OFFICE.

MAX BRESLAUER, OF CHARLOTTENBURG, GERMANY, ASSIGNOR TO THE FIRM OF W. GRAAFF & COMPAGNIE, GES. MIT BESCHR. HAFTUNG, OF BERLIN, GERMANY.

CHEMICAL FIRE-EXTINGUISHER.

No. 876,820.

Specification of Letters Patent.

Patented Jan. 14, 1908.

Application filed January 8, 1906. Serial No. 295,206.

To all whom it may concern:

Be it known that I, MAX BRESLAUER, city chemist and a doctor of philosophy, a subject of the German Emperor, and residing at 5 29 Kleiststrasse, in the city of Charlottenburg, near Berlin, Kingdom of Prussia, and German Empire, have invented a certain new and useful Chemical Fire-Extinguisher, of which the following is a specification.

10 In the chemical fire-extinguishers heretofore employed tartaric acid, sulfuric acid or hydrochloric acid have been used as the acid principle which causes the evolution of carbonic acid and the gas pressure incident thereon for the purpose of effecting the sprinkling, in consequence of the acid acting upon the soda-solution. The employment of these acids was accompanied by various inconveniences. In the first place tartaric 15 acid and hydrochloric acid exert comparatively too feeble an action, so that it was necessary to make use of unreasonably large acid tubes for producing the desired effect and in comparison with the given capacity 20 of the fire-extinguisher; and on the other hand sulfuric acid which on account of its cheapness is used with preference, possesses 25 a too strong and sometimes rather explosive action causing danger of bursting the apparatus, without it being possible to utilize the high pressure generated with advantage for the purpose of a uniform sprinkling of the fire-extinguishing solution. In this connection it has been found by experience when 30 making use of sulfuric acid, that the jet forced out from the apparatus is lacking continuity and particularly in the beginning of the gas-liberating process which is accompanied by the generation of considerable 35 heat of reaction, the jet being thrown around in form of detached pieces to irregular distances and that, generally speaking, it is not possible to obtain any reliable action on account of the considerable decrease of pressure 40 during the sprinkling operation. Nor is it possible to obtain any better results by diluting the sulfuric acid and this dilution causes the inconvenience moreover of necessitating large sized tubes for the acid. These 45 inconveniences and the further practical consideration that it should be attempted if ever feasible, to dispense with as corroding an acid as sulfuric acid and hydrochloric acid, led the inventor to devise an acid substitute 50 of better adaptability than the acids men-

tioned for employment in fire-extinguishers, which substitute before all should have the effect that the pressure of the gas and of the carbonic acid, though exerting a vigorous motive power immediately upon its reacting with the soda solution, yet does not cause the tearing apart of the ejected jet of the fire extinguishing agent, but that on the contrary an enduring sprinkling with continuous jet is caused, the jet showing no essential decrease 60 of its length of throw during the emptying of the apparatus. 65

The invention resides in the fact of employing phosphoric acid in more or less concentrated solution for the charging of the acid tubes in fire-extinguishers in place of other acids. The acid tubes are manufactured from glass in the well-known manner and after having been filled with the acid agent, they are sealed up by fusing the opening together and they are then placed within a solution of acid carbonate of soda, which is the liquid commonly employed for the charging of fire extinguishers, the arrangement of the tubes being such, as to enable them to be 70 broken by means of suitable actuating mechanisms. 75

The advantages which are realized by the use of phosphoric acid according to this invention, are the following: In the first place 80 it should be noted, that even the concentrated solution of phosphoric acid is a comparatively innocuous acid, which does not produce any caustic action or stains that cannot be removed, upon the skin or upon 85 the clothes, as sulfuric acid and hydrochloric acid, in case the tube is broken by inadvertence before it is mounted in the apparatus. In view of the phosphoric acid being very difficultly volatile, the sealing up 90 by fusion of the glass tubes filled with the acid is not accompanied by the inconveniences which arise from the generation of suffocating vapors and gases when sealing up 95 tubes containing sulfuric acid or hydrochloric acid. 100

As regards the efficiency of the acid calculated on the basis of equal volumes, even a somewhat smaller quantity of the solution of phosphoric acid will be sufficient under 105 the same conditions as compared with sulfuric acid; and as compared with hydrochloric acid, it is only necessary to employ one third of the same quantity of phosphoric acid solution. Owing to this fact the tubes 110

may be made correspondingly smaller, so that there is no necessity of facilitating the breaking of the tubes by imparting to them a special shape or by additional auxiliary means, such as are provided for the longer hydrochloric acid tubes for the purpose of greater reliability of action. The economy in space adds to the small weight and to the larger capacity of the apparatus.

10 It has been found by experiments that, when using tubes filled with phosphoric acid in chemical fire-extinguishers of the well-known so-called "Minimax"-type, the efficiency is exceedingly favorable. The jet 15 was thrown to a distance of about 49 feet (as compared with 39 feet in the case of the use of hydrochloric acid) and was maintained in its continuity from the start and it remained under substantially uniform ejecting pressure until the fire-extinguisher was 20 emptied. This novel effect cannot be attained either with hydrochloric acid or with sulfuric acid, no matter whether these acids are concentrated or dilute. The reason for 25 this effect is probably to be attributed to

the fact of the phosphoric acid being capable of setting up a continuously progressing reaction in the mass of soda-solution without excessive heat of reaction under the conditions prevailing in the fire extinguishing apparatus.

The incrustating action, which the mixture ejected by the jet, exercises upon the objects struck by the jet with a view of quenching the flames and the conflagration, 35 is considerably increased on account of the formation of phosphate of soda and in some cases of pyro-phosphate of soda even.

What I claim and desire to secure by Letters Patent of the United States is:—

Chemical fire-extinguisher, in which the filling of the acid-container consists of a solution of phosphoric acid.

In witness whereof I have hereunto signed my name this 27th day of December, 1905, 45 in the presence of two subscribing witnesses.

MAX BRESLAUER.
